F. PEHAM

BED TABLE

Filed July 12, 1926

INVENTOR:

Frank Peham
BY David E. Barlow
ATTORNEY

UNITED STATES PATENT OFFICE.

FRANK PEHAM, OF ST. PAUL, MINNESOTA.

BED TABLE.

Application filed July 12, 1926. Serial No. 121,747.

My invention relates to a combination bed-table and stand, more aptly designated as simply a bed-table, and the object is to provide a table particularly useful for bed-ridden persons but also useful as a stand or small table.

In the accompanying drawing:

Fig. 1 is a side elevation of my improved table in operative position at the side of a bed, the table top proper being shown in section.

Fig. 2 is an enlarged, modified detail of the outer end of the table supporting arm of my device.

Fig. 3 is an enlarged sectional view on line 3—3 in Fig. 2.

Fig. 4 is an enlarged sectional view as on line 4—4 in Fig. 1 showing the bed engaging shoe and its vertically adjustable sleeve.

Fig. 5 is a sectional elevation about as on line 5—5 in Fig. 4.

Fig. 6 is a fragmentary bottom view of the central part of the table base, about as on line 6—6 in Fig. 1.

Referring to the drawing by reference numerals, 5 designates a multiple armed base or spider each arm preferably having a rubber floor contacting button 6. The hub of base 5 is bored for slidably receiving a vertical tubular column 8, said hub having suitable means such as a thumb screw 9 engaged in two parallel tongues 8A extending from the side of the hub and adapted to be sprung toward each other to clamp the column tight.

10 is a horizontal arm suitably clamped or affixed to the upper end portion of the column preferably being held by a thumb-screw 11 clamping clevis jaws 10A about the column. The outer end of arm 10 is offset upwardly comprising a hub 10B bored horizontally for slidable engagement of a tube or rod 12. The ends of the latter (12) are fixed in blocks 13 fastened to the under side of a table 14, the tube 12 thus being fixed in spaced parallel relation to the table and preferably centrally thereof. The hub 10B is preferably made with spaced side wings 10B' engaged by a thumb-screw 15 to clamp the hub at any place on pipe 12. To prevent tilting of the table from a horizontal plane I may provide a longitudinal groove or keyway 12G at the under side of pipe 12 and engaged by a spring pressed pin 16 in the bore of a suitable lug formed on the underside of arm 10 and having a head 16H.

Thus the table 14 is normally retained horizontal but may be readily tilted by releasing pin 16', and the clamping screw 15, then applying screw 15 again to clamp the tube 12 and hold the table at any desired angle. 60

I have illustrated a table with a perimetral flange and which is desirable for setting a meal for a bed-ridden person, but it is obvious that any other type of table may be used.

In Fig. 1, 17 represents either end frame 65 of a bed, 18 is the mattress, 19 the spring and 20 one of the side bars of the spring resting on the side rail 21 of the bed, the latter rail usually comprising an angle-iron bar.

22 is a hollow, vertically elongated housing bored for slidably engaging the column 8, the housing being slotted one way from the column at its upper end, as at 22S, enough to clamp the housing to the column or release it by means of a transversely arranged 70 thumb-screw 23 engaged in its slotted part. Within the slit 22S I place a cam lever 24 fulcrumed on screw 23 at its cam end 24A. This cam 24A is continuously in engagement with the top end 25A of the vertical shank 80 25 slidable vertically within the housing 22 and parallel to the column 8, said vertical shank comprising a part of an L-shaped shoe 25—26. The horizontal part of the shoe, 26, encircles the column 8 loosely, as at 26S 85 Fig. 5, and beyond the column comprises a horizontally disposed upwardly corrugated face 26B. 22L (Fig. 5) is a horizontal ledge in housing 22, bored for insertion of shank 25 upwardly and 27 is a diametral 90 stop pin in shank 25 below ledge 22L and between said pin and the bottom of shell 22 is inserted a compression coil spring 28 which keeps shoe 26 impelled upwardly at all times. The said shoe is thus adapted to 95 frictionally engage the underside or edge of any horizontal element such as the side rail 21 of a bed, as in Fig. 1. To release the shoe from said position it is only necessary to swing the cam lever 24 outwardly and 100 down, as from the dotted to the full line position in Fig. 1, causing the cam 24A to press shank 25 and shoe 26 downwardly enough to release the shoe when it is desired to move the table away from the bed. If 105 the device is to be set for rails 21 at different heights the housing 22 is simply loosened by manipulating screw 23 and raising or lowering the housing on column 8 until shoe 26 bears upwardly against the rail 21, after 110

which screw 23 is again applied to tighten the housing on the column.

It is obvious that the entire device is thus easily set in position at the side of a bed 5 and rigidity maintained by the spring-pressed shoe tending to maintain spreading condition between the floor and the bed rail. The column 8 is also readily set at various elevations and the table 14 rigidly held 10 horizontal or in any desired angle. The device may also be used for general table purposes by fixing its top 14 concentrically above the column 8. It will also be further understood that the frictionally engaged 15 parts such as tube 12 and column 8 may have the various slidable parts fixed to them by means of set-screws, keys and other equivalents (not shown).

What I claim is:

20 In a portable stand of the class described, a base, an upright column slidable and securable in said base, a horizontal arm detachably securable to the upper part of said column, a normally horizontal table supported by said arm, a bar fixed in parallel 25 relation to the under side of said table, means on the outer end of said arm slidably engaging said rod and adapted to hold the

table in any predetermined plane, means mounted on said column and adapted to be 30 fixed thereto at any predetermined elevation and further means adapted to frictionally engage a fixed horizontal element in proximity to the column, said friction means on the column comprising a vertically disposed 35 housing bored for slidably engaging the column, said housing being slotted vertically from its bored part, a transverse pin connecting the opposite parts of said slotted housing and threaded in one of said parts to clamp the housing to the column; and a cam lever fulcrumed on said transverse pin, the lever of said cam exteriorly of the housing and the cam adapted to be actuated downwardly 40 within the housing, an L-shaped shoe, the horizontal arm of said shoe adapted to engage upwardly a fixed element in spaced relation to the column, a compression coil spring about the vertical arm of said shoe 45 and arranged to continuously impel the shoe upwardly, the upper end of said vertical arm normally in frictional contact with the said cam and said shoe from the fixed element.

In testimony whereof I affix my signature.

FRANK PEHAM.
